[57] **CLAIM**

The ornamental design for a cabinet, as shown and described.

DESCRIPTION

FIG. 1 is a perspective view of a cabinet showing my new design;

FIG. 2 is a front elevational view thereof;

FIG. 3 is a top plan view thereof;

FIG. 4 is a right side elevational view as seen when in use;

FIG. 5 is a left side elevational view as seen when in use;

and,

FIG. 6 is a perspective view of a second embodiment of the cabinet shown in FIG. 1, the opposite side being a mirror image thereof.
